UNITED STATES PATENT OFFICE.

MERITT L. PHELPS, OF COLORADO CITY, COLORADO.

ANTI-RAIL-CREEPING DEVICE.

1,063,060.

Specification of Letters Patent.

Patented May 27, 1913.

Application filed February 10, 1912. Serial No. 747,484.

To all whom it may concern:

Be it known that I, MERITT L. PHELPS, a citizen of the United States, residing at Colorado City, county of El Paso, State 5 of Colorado, have invented certain new and useful Improvements in Anti-Rail-Creeping Devices; and I do hereby declare the following to be a full, clear, and exact description of the invention, such as will enable others 10 skilled in the art to which it appertains to make and use the same.

This invention relates to certain improvements in means for preventing railroad rails from creeping; and the objects and nature of 15 the invention will be readily understood by those skilled in the art in the light of the following explanation of the accompanying drawings illustrating what I now believe to be the preferred mechanical expression, or 20 embodiment, of my invention from among other formations and arrangements within the spirit and scope of the invention.

An object of my invention is to provide simple and efficient means to prevent running 25 or creeping of railroad rails and to maintain the proper spacing of the ties, and at the same time to avoid locking the rails so immovable and fixedly to the ties or tie plates as to prevent independent expansion 30 and contraction of the individual rails under the influence of climatic or temperature conditions.

A further object of the invention is to provide means for preventing the creeping of 35 railroad rails and at the same time bracing and strengthening said rails, embodying transversely arranged corrugations on the bottom face of the rail base formed in the process of making the rail by rolling or 40 swaging the metal thereof to produce comparatively long rolling rounded or curved corresponding transverse valleys and ridges constituting a so-called waving corrugation effect.

45 The invention consists in certain novel features in formation and in combinations and arrangements as more fully and particularly set forth hereinafter.

Referring to the accompanying drawings, 50 Figure 1, is a perspective view showing a portion of a railroad rail constructed in accordance with my invention. Fig. 2, is a perspective view of the rail and tie plate assembled on a tie, the securing spikes not

being shown. Fig. 3, is an elevation of the 55 rail, plate and tie. Fig. 4, is a detail perspective of the tie plate.

In the drawings, I show part of a rail 1, having the bottom of its base 2, corrugated by uniformly spaced similar parallel transverse concavities or valleys 3, and intervening parallel ribs or ridges 4, all similar to each other but preferably not formed by curves of the same radius as those of the valleys, usually so that the corrugations are 60 rolling or wavy, but I do not wish to so limit my invention. The valleys and ridges preferably extend from one longitudinal edge of the base to the opposite edge thereof and the corrugations extend preferably through 65 out the length of the rail.

The rail base is corrugated in the process of manufacture and while heated by swaging, forging or pressing so that the completed rail will be stiffened and strengthened 70 by the formation and presence of the corrugations. The rail is preferably corrugated by suitably formed rolls or dies during the rolling process although my invention is not so limited. Where the corrugations are 75 formed by thus pressing the metal of the rail the finished product is strengthened, whereas the rail is seriously weakened by transverse or other cuts that sever the grain or fiber of the metal or form starting points 80 or lines for breaks. Railroad rails having the bottom faces of their bases formed with corrugations, will, when properly seated on 85 ties or supports formed to receive the same, tend to hold said ties or supports properly 90 spaced, and resist rail creeping or running.

My invention particularly contemplates a tie plate corrugated for use in combination with said corrugated rail. I show a tie plate 5, formed to rest on a tie and extend 95 transversely beneath the rail and project in opposite directions beyond the same. The plate is formed with spike holes 6, approximately at the corners thereof to receive spikes (not shown) for securing the plate 100 to the tie and so that the spike heads will lap over the rail base and secure the same to the plate.

The plate is formed at its top face with a raised edge or shoulder 7, to engage the 105 outer longitudinal edge of the rail base and thereby brace the rail against spreading or displacement, while the under face of the

plate can be formed with ribs 8, to sink into the tie and thereby aid in holding the plate against movement on the tie. The top surface of the plate traversed by and receiving the corrugated bottom of the rail base is approximately correspondingly formed with parallel valleys 9, and ridges 10, or in other words, is corrugated to receive and mesh with the corrugations of the rail to most effectively lock the rail to the tie against creeping or running. However, the ridges 10, of the plate are narrower than the valleys of the bottom surface of the rail and do not fill the full width of said valleys. Open spaces hence intervene between the opposite sides of the ridges of the rail bottom so that the rail is free to longitudinally expand and contract to a limited extent independently of and slideable on the plate. In other words, the individual rail can move the ridges of its corrugations on the plate and between the ridges thereof. The plates are corrugated at the mill by rolling, pressing or stamping and the plates are thereby braced and strengthened.

A serious difficulty in anti-creeping devices for rails as heretofore proposed, is overcome by my invention, inasmuch as where it has heretofore been possible to rigidly fix and lock the rails to the ties against longitudinal movement independently of the ties, a more serious and dangerous condition resulted than thereto existed, due to the individual expansion and contraction of the rails under temperature changes. The contraction and expansion of rails rigidly fixed to tie plates and ties will necessarily destroy the connections thus established and result in most dangerous conditions.

The dangerous track conditions and accidents that result from buckled track, rails that "kick out," and broken rails, caused by creeping, are well understood and many efforts have endeavored to solve the problem, and railroads have spent large sums in efforts to overcome the difficulty, but according to my information and belief these efforts have not been wholly successful and satisfactory.

My invention attains the desired result inasmuch as the rails are held to the ties against creeping or running while the allowance of space laterally between the engaging bearing surfaces of the rail and plate provide for the expansion and contraction of each individual rail without disturbing the anti-creeping lock between the rails and ties.

My invention contemplates a rail base having depressions and bearing surfaces and a support having depressions and bear-

ing surfaces with allowance to permit contraction and expansion of the rail.

It is evident that various changes, variations and modifications might be resorted to without departing from the spirit and scope of my invention and hence I do not wish to limit myself to the exact disclosure hereof.

What I claim is;—

1. A railroad rail having the floor of its base formed with wave-like corrugations pressed therein, in combination with a tie plate having wave-like corrugations pressed in its top face and meshing with said corrugations of the rail.

2. A railroad rail having its base formed with series of transversely-disposed depressions and intervening ridges, in combination with a tie plate having ridges entering said depressions to hold the rail against creeping, said ridges and depressions of the rail and plate being so relatively formed as to provide lateral spaces to allow for expansion and contraction of the rail independently of the tie plate.

3. A railroad rail having the bottom face of its base formed with uniformly spaced parallel transversely-arranged valleys and intervening ridges pressed therein, in combination with a tie plate formed for being fixedly secured to a tie and having parallel transverse valleys to receive the ridges of said rail and intervening ridges to enter the valleys of the rail, said ridges being less in width than said valleys for the purpose described.

4. A railroad rail having the bottom face of its base corrugated in combination with a support therefor having its top face corrugated to mesh with the corrugations of the rail, lateral spaces intervening between the intermeshing bearing surfaces of the rail and support to allow for expansion and contraction of the rail independently of and on the support.

5. A railroad rail having the under face of its base formed with transversely curving corrugations pressed therein in combination with a tie plate having corrugations pressed in its top face and adapted to mesh with the corrugations of the rail to hold the rail against creeping.

6. A railroad rail having the floor of its base formed with wave-like corrugations, in combination with a tie plate having wave-like corrugations in its top face meshing with said corrugations of the rail.

In testimony whereof I affix my signature, in presence of two witnesses.

MERITT L. PHELPS.
